ATTORNEY

UNITED STATES PATENT OFFICE.

LUCIUS O. WALDO, OF BELLINGHAM, WASHINGTON.

ADJUSTABLE CAN-HANDLER.

1,288,770.

Specification of Letters Patent. Patented Dec. 24, 1918.

Application filed July 17, 1917. Serial No. 180,975.

To all whom it may concern:

Be it known that I, LUCIUS O. WALDO, a citizen of the United States, residing at Bellingham, in the county of Whatcom and 5 State of Washington, have invented a new and useful Adjustable Can-Handler, of which the following is a specification.

My invention relates to adjustable can handling devices used by canners of food products, and the object of my invention is to provide a hand implement of strong, light and simple construction with which an operative may quickly remove a number of cans at once from the roller chain of a can lacquer machine, where they are in open order, without soiling the soft lacquer, and retract the device to put the cans in close order and place them in a case or other receptacle; also which may be used to remove 15 cans from cases, or other place where they are in regular order, and deposit them *en bloc* in another location.

I attain this object by the mechanism illustrated in the accompanying sheet of drawings in which—

Figure 1 is a plan view of my device when protracted, Fig. 2 is an end elevation view of Fig. 1, Fig. 3 is a side elevation view of Fig. 1, Fig. 4 is a side elevation view in section on the line *b*—*b* of Fig. 5 of some of the conveyer rollers of a can lacquering machine, Fig. 5 is a plan view of a portion of the rear part of a can lacquering machine, and Fig. 6 is a front elevation view of a 30 case of cans showing the forks of my device in section on the line *a*—*a* of Fig. 1, but retracted, in engagement with the top layer of cans in said case.

Similar characters refer to similar parts in 40 the several views. Certain parts are broken away in order to show others hidden thereby.

My device comprises a rectangular, tubular frame consisting of front member 1, rear member 1^a and end members 1^b and 1^c; rotatable handles 2, 2 on frame ends 1^b and 1^c; fork heads 3, 3, 3^d, 3^d, 3^e, 3^e, slidable on front frame member 1; fork handle slides 3^c, 3^c, etc., slidable on rear frame member 1^a; fork handles 3^b, 3^b, etc.; forks 4, 4, etc.; handle

cranks 6, 6; connecting rods 5, 5, 5^a, 5^a, 5^b 50 and 5^b; and stop rings 7, 7.

Each of handle cranks 6 has three holes. Connecting rods 5^b join fork heads 3 with handle cranks 6 at the inner of said holes, connecting rods 5^a join fork heads 3^d with 55 cranks 6 at the middle holes, and connecting rods 5 join fork heads 3^e with cranks 6 at the outer holes. Said holes in cranks 6 are equally spaced and forks 4 are moved by the turning of handles 2 toward or from each 60 other distances which vary in arithmetical proportion. By turning handles 2, 2 inward handle cranks 6, 6 are moved to their dotted positions at 6', 6' Fig. 3 and the six forks 4, 4, etc. are moved toward the center to their 65 dotted positions at 6', 6', etc., when they are in their retracted positions, and the middle fork heads 3, 3 bear on each other. But when said forks are in their protracted positions, illustrated in full lines, the end fork 70 heads 3^e, 3^e bear on stop rings 7, 7.

To use my device: An operative grasps a handle 2 in each hand and maintains forks 4 in their protracted position by turning handles 2, 2 outward as far as they will move; 75 while the forks are in this relative position they are introduced beneath twelve cans A, A, etc. on the conveyer rollers 8, 8, etc. of a lacquering machine, see Fig. 5; here the tines are associated with rollers 8 and cans A as 80 shown at 4, 4, etc., in Fig. 4. The operative then raises the device, lifting the group of twelve cans from rollers 8, 8, etc., when cans A appear on forks 4 as in Fig. 1. By turning handles 2 inward the forks are moved 85 toward each other until cans A touch each other. In this retracted position of the handler it is carried with said load of cans to case B and the twelve cans placed therein where they make one tier, as in Fig. 6, where 90 fork tines 4 are shown in engagement with the upper tier or layer of cans in said case. After this the retracted carrier forks are removed from said case and again protracted as before when they may be used to remove 95 another lot of cans from said rollers.

It is apparent that while my carrier is in its retracted form it may be used to pick up

cans lying in regular order, sides touching, and carry them *en bloc* for placing in any desired location.

I claim:

- 5 In a can handler in combination, a frame, a plurality of forks, a fork head rigidly attached to each of said forks, and slideable on said frame, two revolute handles, a crank

rigidly attached to each of said handles, and a connecting rod between each of said fork heads and one of said cranks.

Signed at Bellingham, in the county of Whatcom and State of Washington this 12th day of July, 1917.

LUCIUS O. WALDO.
